UNITED STATES PATENT OFFICE.

OTTO BUSSLER, OF NUERMBERG, BAVARIA, GERMANY.

STYLOGRAPHIC PEN.

SPECIFICATION forming part of Letters Patent No. 350,037, dated September 28, 1886.

Application filed April 7, 1885. Renewed August 16, 1886. Serial No. 211,068. (No model.)

To all whom it may concern:

Be it known that I, OTTO BUSSLER, of Nu-
remberg, Bavaria, Germany, have invented a
new and useful Stylographic Pen, of which
5 the following is a specification.

This invention relates to copying-ink pencils or stylographic fountain-pens.

In describing the invention reference will be made to the accompanying drawings, Figures I to III, of which Figs. I and II are longitudinal sections of a pen embodying my invention, while Fig. III represents a detail.

The improvement chiefly consists in a device for protecting the point, and in the arrangement for adjusting the pencil for use.

Hitherto the device for protecting the point *s* and the ink-reservoir *t*, connected with the same, merely consisted in a sleeve adapted to be pushed over the point, which arrangement 20 is not sufficient to protect the point *s* against impurities.

The copying-pencil embodying this invention is provided with an automatic perfectly-acting device for protecting, and at the same 25 time holding, the point.

The invention consists in the application of a divided clamp, *k*, adapted to close completely, in combination with the point *s* of the ink-reservoir, provided with a recess (or a swelling or projection) for the combined purpose 30 of protecting the point when not used and holding the same when used.

The apparatus is constructed as follows:

t is the ink-reservoir, moving freely in the 35 interior and completely independent from the surrounding sleeve. The reservoir contains a pencil passing through its whole length and provided with a piston and spring for the automatic feed of the ink.

g is the india-rubber disk, serving to close 40 the upper end of the ink-reservoir when the pen is not in use. When used, the pencil is pushed back, the india-rubber disk is lifted and admits air, whereby the ink is discharged

at the lower end in the usual manner. The 45 ink-reservoir *t* is surrounded by a tube, *r*, with the divided elastic mouth-piece of the clamp *k*. The clamp *k* may be closed by the ends of the tube *h*, which moves up and down along the tube *r*, and opened (spread) by the wedge-shaped teeth *e*, mounted near the lower end of the tube *h*. When closed, this clamp completely covers the point *s*. This operation is effected automatically by the spring *f*, which constantly tends to draw the tube *r*, with clamp 55 *k*, into the tube *h*.

For using the copying-pencil, the point is held downward and the tube *r* is pushed down into the tube *h*. By holding the point downward the movable ink-reservoir *t* falls downward. By the pressure on the tube *r* the clamp *k* is pushed out and disengaged from the ends of the tube *h* and opened by the teeth *e*, so that the ink-reservoir *t* can freely advance (until it reaches a suitably-situated stop) so as to protrude from the clamp *k*. The point *s* is provided with recesses *i*, or a lateral detent, (collars or projections, &c.,) in which the clamp *k* engages when the pressure at the upper end (on tube *r* and spring *f*) ceases, whereby the 70 copying-pencil is arrested and held fast.

What I claim is—

The combination of a movable ink-reservoir having recesses *i*, or a lateral detent, with an expandible clamp, *k*, adapted to either close 75 together in front of the point of the reservoir or to engage with the recesses *i*, or detent of the same, for the purpose of holding the reservoir in position when in use and protecting the point when not in use, substantially as de- 80 scribed.

In testimony whereof I have signed this specification in the presence of two subscribing witnesses.

OTTO BUSSLER.
